FEEDING MECHANISM FOR PRINTING PRESSES

Joseph F. Jirousek, Cleveland, Ohio, assignor to
The Chandler & Price Company, Cleveland,
Ohio, a corporation of Ohio

Application October 13, 1939, Serial No. 299,308

6 Claims. (Cl. 271—20)

This invention relates, as indicated, to feeding mechanism for printing presses and especially for presses of the lithographic or offset type.

A primary object of this invention is to provide a sheet feeding mechanism adapted to transport a large number of sheets to the impression cylinder in a short space of time but without requiring rapid movement of such sheets en route from stack to cylinder.

Another object is to provide such mechanism which is also easily adjustable and whose parts are readily accessible.

A further object of this invention is to provide sheet feeding means including novel sheet picker means of improved efficiency and positive action.

Other objects of this invention will appear as the description proceeds.

To the accomplishment of the foregoing and related ends, said invention, then, consists of the means hereinafter fully described and particularly pointed out in the claims.

The annexed drawings and the following description set forth in detail certain mechanism embodying the invention, such disclosed means constituting, however, but one of various mechanical forms in which the principle of the invention may be used.

In said annexed drawings—

Fig. 1 is a top plan view of the feeding mechanism of this invention;

Fig. 2 is an enlarged fragmentary view of a portion of the mechanism shown in Fig. 1;

Fig. 3 is a side elevational view of the sheet corner buckling means taken on line 3—3 on Fig. 2;

Fig. 4 is an elevational view of the sheet elevating means taken on line 4—4 on Fig. 2;

Fig. 5 is an elevational view in cross-section of the suction means illustrated in Fig. 4;

Fig. 6 is an elevational view of the air blast means taken on the line 6—6 on Fig. 2;

Fig. 7 is another view of said air blast means and guide means therefor shown partly in cross-section taken along the line 7—7 on Fig. 6;

Fig. 8 is a front elevational view of one sheet elevating assembly taken on the line 8—8 on Fig. 2;

Fig. 9 is a view along the line 9—9 on Fig. 8 of the rear edge stack gauge;

Fig. 10 is an elevational view of the sheet moving means taken on the line 1—10 on Fig. 2;

Fig. 11 is a view in cross-section along the line 11—11 on Fig. 1 of a portion of the sheet conveyor driving means;

Fig. 12 is a cross-sectional view taken on the line 12—12 on Fig. 2 of said sheet conveyor driving means;

Fig. 13 is a cross-sectional view taken on the 60

line 13—13 on Figs. 1 and 14 of the sheet conveyor mechanism;

Fig. 14 is a top plan view of a portion of said conveyor;

Fig. 15 is an elevational view showing the air and suction supply systems;

Fig. 16 is an elevational view in cross-section of the sheet feeding mechanism from stack to cylinder;

Fig. 17 is a diagrammatic representation in elevation of the sheets as they pass from stack to cylinder showing their overlapping relationship; and

Fig. 18 is a top view of such sheets as shown in Fig. 17.

Referring now more particularly to said annexed drawings and especially Figs. 1, 2, 3, 4, 5, 6, 7, 8, 9 and 10, the sheet feeding mechanism of this invention comprises sheet picker means 5 adjustably mounted on the frame 1 of the press and sheet conveying means for transporting the sheets to the impression cylinder 2.

The sheet picker assembly is constituted as follows: Attached solidly to the frame 1 of the press and on either side of the feed table which supports the stack 3 are racks 4 and 4' on which move pinions 5 and 5'. At each end of pinion shaft 6 and supported on sleeves embracing said racks 4 and 4', are end members 7 and 7' which carry cross-shafts 8, 9, 10 and 11 therebetween. Shafts 9, 10 and 11 are hollow, shaft 9 being adapted to carry compressed air and shafts 10 and 11 being connectible to a vacuum line. Shaft 8 is rotatably mounted in bushings in said end members 7 and 7' with a bevel gear 12 at one end. Engaging said gear is another bevel gear 13 slidably keyed to a shaft 14 by means of a groove 15 in said shaft. Said gear 13 may be fixedly positioned on said shaft 14 by means of a set screw 16 which effectively prevents movement of said pinions on said racks in a direction toward said impression cylinder. Movement in the other direction is prevented by a sleeve 17 about said shaft 14 which is bolted to the end member 7. By means of bevel gears 18 and 19, power is derived from the cross drive shaft 20 when the pin 21 is in engagement with the slot 22 in gear 19. As shown in Fig. 2 said pin is in disengaged position and gears 19 and 18 would not be turning. Conventional clutch means controlled by cam lever 23 are employed to effect such engagement and disengagement.

Adjacent rear corners of the stack, on shafts 8, 9 and 10, are mounted sheet pick-up units 55 identical but for the fact that one is the mirror image of the other. One of these units is shown in top plan in Fig. 2 and in elevation in progressive sections in Figs. 3, 4, and 6. Each unit comprises an outer, substantially U-shaped frame member 24 mounted on the work shaft 8 and hol-

low shaft 9 and encompassing the mountings of the other elements whereby a proper relationship of the same may be maintained and the whole unit moved together on the cross shafts when adjustment is made for different sheet sizes.

Within said U-shaped member and mounted on shaft 9 is a supporting member 25 kept from pivoting about said shaft 9 by means of a fork 26 engaging shaft 10. Mounted in a boss 27 on said member 25 is a pin shaft 28 to which are fixed arms 29 and 30. Said arm 29 carries a roller 31 which is held in contact with the face of cam 32 by means of the torsional spring 33, said cam being keyed to shaft 8. Slidably housed at the other end of arm 30 is a vertical rod 34 prevented from turning in the housing 35 and whose vertical movement is limited by a pin 36 in a slot 37. To the lower end of said rod 34 is attached a mounting 38 for a rubber shoe 39. Said shoe is constantly pressed on top of the stack 3 by means of a coil spring 40 interposed between said housing 35 and said mounting 38. It will thus be seen that as shaft 8 rotates the cam 32 acts through roller 31, arm 29, pin shaft 28, arm 30, and rod 34 to move said shoe 39 back and forth in an arc about the axis of said shaft 28.

To the forward end of member 25 is attached a horizontal rod 41 and at the end of said horizontal rod a vertical rod 42 is mounted in a mount permitting angular adjustment and extension. A wire 43 extending from the foot of said vertical rod 42 presses down on the upper edge of the stack 3 a few inches forward of the corner adjacent which said shoe 39 operates.

Another rod 44 extends from the forward end of member 25 parallel to the rear edge of said stack. On its end is pivotally mounted an arm 45 which carries a rubber shoe 46 adapted to bear on the rear edge of the stack. Continuous pressure is maintained by means of a torsional spring 47. (See Figs. 8 and 9.)

Also attached to the forward end of member 25 is a small flat bar 48 parallel to the rear edge of the stack. At its end slidably mounted in a housing 49 is a vertically disposed rod 50 carrying a metal foot 51 near its lower extremity. Said foot is kept pressed against the upper edge of said stack by means of a spring 52 between said foot and said housing. The portion of said rod 50 below said foot contacts the rear side of said stack. Said foot 51 acts as a hold-down but permits the movement of shoe 39 to buckle the top sheet between the rubber shoe 46 and the wire 43, the edge of such sheet slipping from under said metal foot which then rests on the second sheet and keeps the same in place. A wire hold-down such as 43 has also been found to be satisfactory. The disposition of the above-described shoes, feet and hold-downs is best illustrated in Figs. 3, 8 and 9.

Mounted within the compass of said frame member 24 are two other elements of the unit, the sheet grasping means and the air blast means.

Said sheet grasping means comprises a frame piece 53 pivotally mounted on shaft 9. It is further supported by a roller 54 resting on the cam 55 keyed to shaft 8, said cam imparting a rocking action to said frame piece as shaft 8 rotates. Said roller is held in close association with said cam by means of a spring 56 between said frame piece 53 and said member 25.

A block 57 is pivotally mounted on the side of said member 25 adjacent said frame piece 53.

Through said block and slidably therein passes a tube 58 closed at its lower end and supported by a clamp 59 and stub pin 60 fitting in a slot 61 in the end of said frame piece 53. Said tube 58 is tapped by a rigidly affixed tube 62 carrying another vertical tube 63. The lower end of said last named tube is open and inserted therein is a stub tube 64 with a rubber sucker tip 65 at its end. (See Fig. 5.) A pin 66 on said stub tube fits in a slot 67 in said vertical tube 63 and limits the possible relative vertical movement. Inside said tube 63 a coil spring 68 acts on the inner end of tube 64 to keep such latter tube at its lower limit. As a result, jarring which might damage the mechanism is avoided. A rubber tube connects the nipple 69 with hollow shaft 11 through which suction is intermittently applied as described below.

The air-blast means comprises a frame piece 70 pivotally mounted on shaft 9 and further supported by a roller 71 resting on a cam 72 keyed to shaft 8, as best shown in Fig. 6. At the forward end of said frame piece 70 is a pivotally mounted clamping block 73 holding a tube 74 with its lower end bent and flattened to provide a narrow orifice 75. The lower portion of said tube is held in a clamp 76 (shown in cross-section in Fig. 7) which carries a cam roller 77 which runs in the cam slot 78 in the angular member 79 secured to the end of arm 25. Thus, as the cam 72 rotates, the tube 74 is reciprocated and the lower end moved forward on each down stroke. A nipple 80 at the upper end of said tube is connected to hollow shaft 9 by rubber tubing through which compressed air is intermittently passed to exit at said orifice 75.

The operation as a whole of the above described sheet pick up unit will be detailed below in conjunction with that of the other parts of the assembly. As noted above and illustrated in Fig. 1, a like pick up unit is located in a like position at the other corner of the stack and the two operate in unison.

Centrally positioned between said sheet pick up units is an assembly for advancing the sheet to the sheet conveying means, being best shown in Figs. 2 and 10. Said assembly comprises two adjacent units (one a mirror image of the other) acting in unison. A rectangular block 81 is mounted on shaft 8 within a U-shaped member 82. The upper portions of the arms of said U-shaped member are bridged by a plate 83 carrying a cam roller 84 which rides on the cam 85 and thus supports said member 82. Coil springs 86 and 87 keep cam 85 and roller 84 in close contact. Piercing the upper ends of said U-shaped member and slidably mounted therein is a rod 88. A member 89 is pivotally attached to the lower portion of said U-shaped member and connected to said rod 88 by means of the link 90, one end of said link being pivotally attached to the clamp 91 on said rod. A roller 92 is mounted on said member 89 in position to contact the cam 85 which in its rotation thus acts to reciprocate rod 88.

At the forward end of said rod 88 a short vertical rod 94 descends to a clamp 95 which embraces a horizontal rod 96 (this same rod is embraced by corresponding clamp 95' of the other unit of the assembly, thus joining the two). Positioned on this rod 96 is clamp 97 which houses a vertically slidable tube 98. Said tube is bent forwardly and downwardly and terminates in a rubber sucker tip 99. A coil spring 100 interposed between said clamp housing 97 and the

bend in tube 98 serves to maintain said sucker tip 99 in depressed position relative to said clamp housing and eliminates jarring and possible damage if said tip should accidentally strike the top of the stack. The nipple 101 at the upper end of said tube 98 is connected by rubber tubing to hollow shaft 10 through which suction is intermittently applied. A like sucker assembly is held by clamp 97' toward the other end of rod 96 (see Fig. 1).

A coil spring 102 compressed between stop 103 and the near arm of the U-shaped member 82 serves to maintain roller 92 in constant contact with cam 93. An arm 104 affixed to said block 81 and embracing shaft 9 serves to prevent pivotal movement of the whole unit about shaft 8. It will now be seen that rotation of shaft 8 with consequent rotation of cams 85 and 93 will result in both vertical and horizontal reciprocation of sucker tip 99 as more particularly described below.

The drive shaft 20 derives its power from a sprocket and chain (not shown) and turns the conveyor drive shaft 105 through gear 106, reduction gearing 107, and gears 108 and 109. (See Figs. 11 and 12.) Said conveyor drive shaft 105 may be stopped or started at will by means of the clutch 110 controlled by lever 111 and link 112 operated by a cam lever (not shown) adjacent lever 23.

Three woven tape belts 113 pass about said shaft 105 and freely turning shaft 114. Two other belts 115, one on each side of said aforementioned belts, pass about freely turning shaft 116. Tension is maintained in the belts by means of belt-tighteners 117 such as that illustrated in Figs. 12 and 13. The wooden table 118 beneath the conveyor belts has a large glass insert 119 which together with a light bulb placed thereunder facilitates inspection of the water fountain, dampening rollers, cylinders, etc., of the press.

Cross shaft 120 serves as a pivotal mount for a pair of L-shaped arms 121 and 121' (see Figs. 1, 2 and 16). The assembly of arm 121 will be described, it being understood that that of arm 121' is similar. A roller 122 at one end of said pivotal arm contacts a cam 123 on the drive shaft 20, causing the forward end of said arm to move up and down in an arc about the axis of shaft 120. A pivotally mounted extension 124 of said arm carries a roller 125 adapted to contact one of the tapes 113 as it passes over conveyor-drive shaft 105 (or to rest on the sheets passing therebetween). A compression spring 126 and an adjustable stop serve to adjustably position extension arm 124 and keep the same from bearing down too severely or tipping back when the cam action raises roller 125.

A flat cross-bar 127 attached to the frame 1 supports a pair of brackets 128 and 128' each carrying similar assemblies. That of bracket 128 will be described as illustrative of both (see Figs. 13 and 14). A bar 129 is held in said bracket and extends forwardly therefrom. Also supported in a boss 130 on said bracket and adjustably positioned therein by means of a set screw 131 is a small vertical rod 132 carrying a horizontal rod 133 having an upturned rear end. By proper adjustment of said vertical rod said horizontal rod may be positioned slightly above the level of the conveyor tapes to hold the sheets closely thereon. Similar rods 134 and 134' are held in brackets 135 and 135' and carry small tabs at

their ends which effectually smooth out any curl at the edge of the sheet.

Approximately midway on bar 129 a bracket 136 is adjustably positioned. Pivotal mounted on a bolt 137 inserted in said bracket are a brush 138 and an arm 139, said arm carrying a roller 140. A torsional spring 141, also somewhat compressed, between the head of said bolt and said arm acts to press said brush and roller downwards to keep the sheets pressed against the conveyor tapes.

An arm 142 is pivotally mounted on a bolt 143 inserted in bracket 128 with torsional spring 144 acting to turn said arm downwardly. A fibre roller 145 is carried at the end of said arm.

Another bracket 146 is adjustably positioned on rod 129 and arm 147 pivotally mounted thereon. An adjustable screw 148 bears on one end of said arm, elevating the other end of said arm as it is depressed. The other end of said arm houses a rotatable metal ball 149 the lower portion of which is adapted to rest on the sheets passing thereunder.

Side gauges 179 mounted on an oscillating cross-rod 150 gauge the sheets just before they are fed to the impression cylinder 2.

The controls for the conventional stack elevating means are also illustrated in Fig. 2, comprising a feeler finger 151 mounted on rod 152 which rod is rocked by the reciprocating partial rotation of shaft 153. Said shaft is turned by arm 154 as the latter is raised and lowered by roller 155 running against cam 156. As sheets of arm 157 is raised permitting progressive elevation of the stack. The mechanism therefor is well known to those skilled in the art and forms no part of the present invention.

The air blast and suction means are automatically controlled as illustrated in Fig. 15. A cam 158 on the end of shaft 20 acts on roller 159 to reciprocate arm 160 in an arc about its pivotal mounting 161. A spring 162 holds said roller in constant contact with said cam. A link 163 connects the end of said arm with valve actuating lever 164 which operates rotary valve 165. Said valve controls the suction in hollow shaft 10 by way of flexible tubing 166 which it connects with vacuum line 167. Said vacuum line also connects with hollow shaft 11 by way of flexible tubing 168 and 169 intercepted by slide-valve 170. Said last-named valve is controlled by a cam 171 on the end of shaft 8 which contacts roller 172 on the slide of said valve. A similar valve 173 actuated by cam 174 on shaft 20 controls the flow of compressed air passing through turncock 175, tubing 176, hollow shaft 9, and thence to air-blast tubes 74.

The operation of the above described sheet feeding mechanism is as follows: With hold-downs 43 and 46 resting on the stack rubber shoes 39 buckle up the two rear corners of the top-most sheet. Sucker tips 65 contact the bulged portion of said sheet, the suction comes on, and said tips raise the rear edge of said sheet about one inch above the top of the stack, the buckler shoes 39 retracting as the tips take hold. Simultaneously with the rising action of said tips the air-blast tubes 74 move downward and forward so that at the top of the rise of said tips said tubes are resting on top of the next sheet on the stack, holding the same down. Then the air-blast comes on, floating the first sheet, the aforesaid sucker tips 65 release their hold, and 75 sucker tips 99 descend to meet said sheet and

seize and advance the same, the forward portion being floated by said air blast.

The forward edge of said first sheet is thus advanced to a point slightly beyond roller 105; the air-blast ceases, rollers 125 descend to hold said sheet firmly against the conveyor belts 113 and 115, and the sheet is then continuously advanced by said belts. Should the sheets become clogged or crumpled the conveyor may be disengaged by use of the clutch 110, permitting prompt remedial action without stopping the press or carrying such improperly disposed sheets to the impression cylinder where more serious trouble might arise.

After the above-described movements of the sheet picker means the units return in position to repeat the cycle. This is so timed that the second sheet is advanced underlying the first sheet by somewhat more than one-half its breadth (it will be understood that this may be varied to suit the circumstances), the rollers 125 being raised as the forward edge of such sheet is advanced thereunder. The third sheet and all thereafter are similarly advanced, all three sheets overlapping, to some extent. It will thus be seen that an overlapping feed is obtained permitting the conveyor to run at less speed than would otherwise be necessary. The arrangement and progressive movements of such sheets is best seen in Figs. 16, 17 and 18.

The sheets pass under rollers 145, 140 and 149, the most forward sheet passing from beneath rollers 145 and 140 and being pressed down by brushes 138 and ball rollers 149 which permit gauging of the sheet. Brackets 136 and 146 may be positioned where desired on rods 129 to accommodate various sizes of sheets. The forward edge of the foremost sheet on the conveyor abuts against stops 177 which retract just prior to the arrival of sheet gripping jaws 178 of the impression cylinder 2. As it is gripped, the next sheet takes its place, each sheet remaining momentarily stationary in this position although the conveyor is continuously bringing along the following sheets.

The mechanism of this invention has proven very advantageous in providing reliable and rapid feed from stack to cylinder without too rapid movement of the sheets, is easily adjustable, and may be operated by one without special skill or training.

Other modes of applying the principle of my invention may be employed instead of the one explained, change being made as regards the mechanism herein disclosed, provided the means stated by any of the following claims or the equivalent of such stated means be employed.

I, therefore, particularly point out and distinctly claim as my invention:

1. In sheet feeding mechanism for printing presses and the like, means for buckling the two rear corners of the top-most sheet on a stack, said means comprising frictional means and hold-downs adjacent said corners continuously bearing on such stack, suction means operative to seize the resultant buckled portions of said sheet and elevate the rear edge thereof, air-blast means interposable between said top-most sheet and the next sheet of the stack and operative to float said top-most sheet, and suction means operative to seize and horizontally advance said top-most sheet, the forward edge thereof being floated by said air-blast.

2. The method of separating a sheet from a stack preparatory to conveying the same to a printing press or the like which comprises buckling the rear corners of said sheet, seizing the resultant buckled portions by suction means and elevating the rear edge of said sheet thereby, interposing air-blast means between said sheet and the next sheet below, floating said sheet by means of said air-blast, and seizing the rear portion of said sheet and horizontally advancing said sheet thus floated by further suction means.

3. In sheet feeding mechanism for printing presses and the like, means for buckling the two rear corners of the top-most sheet on a stack comprising cam-operated frictional means reciprocable in a horizontal plane and hold-downs adjacent said corners, suction means operative to seize the resultant buckled portions of said sheet and elevate the rear edge thereof comprising cam-operated sucker tips, air-blast means interposable between said top-most sheet and the next sheet of the stack and operative to rest on said latter sheet, and further cam-operated suction means operative to seize and advance said top-most sheet, the forward edge thereof being floated by the air-blast from said air-blast means.

4. In sheet feeding mechanism for printing presses and the like, means for buckling the two rear corners of the top-most sheet on a stack, each of said means comprising a friction shoe, cam-operated means for rocking said shoe in a horizontal plane, and hold-down means bearing on the rear and side edges of the stack adjacent the rear corners thereof, suction means operative to seize the resultant buckled portions of the sheet and elevate the rear edge thereof, air-blast means interposable between such elevated sheet and the next sheet of the stack, and further suction means operative to seize the rear portion of such sheet and advance such sheet, the forward edge thereof being floated by the air-blast from said air-blast means.

5. In sheet feeding mechanism for printing presses and the like, means for buckling the two rear corners of the top-most sheet on a stack, each of said means comprising a friction shoe, cam-operated means for rocking said shoe in a horizontal plane, and hold-down means continuously bearing on the rear and side edges of the stack adjacent the rear corners thereof, suction means operative to seize the resultant buckled portions of the sheet and elevate the rear edge thereof, air-blast means interposable between such elevated sheet and the next sheet of the stack, and further suction means operative to seize and advance such sheet horizontally, the forward edge thereof being floated by the air-blast from said air-blast means.

6. In sheet feeding mechanism for printing presses and the like, a conveyor positioned between a stack of sheets and the press operative to transport sheets from such stack to such press in lapped relationship, rollers operative to bear on all but the foremost sheet on said conveyor and aligned with the path of movement of said conveyor, and ball roller means operative to bear on such foremost sheet on said conveyor, said means being adapted to facilitate sidewise gauging of such foremost sheet while at the same time maintaining a continuous substantially non-frictional pressure thereon.

JOSEPH F. JIROUSEK.
